UNITED STATES PATENT OFFICE.

WILLIAM H. BETTS, OF ST. LOUIS, MISSOURI, ASSIGNOR TO BETTS SOLE PROTECTOR COMPANY, OF ST. LOUIS, MISSOURI, A CORPORATION OF MISSOURI.

COMBINED PUNCHING AND FORMING PRESS.

Application filed August 23, 1920. Serial No. 405,277.

To all whom it may concern:

Be it known that I, WILLIAM H. BETTS, a citizen of the United States, and resident of St. Louis and State of Missouri, have invented certain new and useful Improvements in Combined Punching and Forming Presses, of which the following is a specification containing a full, clear, and exact description, reference being had to accompanying drawings, forming a part thereof.

My invention relates to improvements in combined punching and forming presses and has for its object a press which will punch and form metal objects complete and is intended primarily for forming my sole protectors, design Patent No. 54718 issued to me March 23, 1920.

A further object is to construct a combined punching and forming press in which U or staple-shaped articles are formed, a complete article being turned out with every stroke of the plunger, except the first stroke.

In the drawings:

Fig. 1 is a front elevation of my device.

Fig. 2 a rear elevation.

Fig. 3 a vertical sectional view taken on the line 3—3 of Fig. 1.

Fig. 4 a front elevation of the column and base with the balance of the mechanism removed.

Fig. 5 a vertical section on the line 5—5 of Fig. 4.

Fig. 6 a top plan view of the punching die.

Fig. 7 a vertical longitudinal cross section of the same.

Fig. 8 a bottom plan view of the section.

Fig. 9 a face view of one of the forming dogs.

Fig. 10 a side elevation of the same.

Fig. 11 a reduced view of the driving shaft.

Fig. 12 a cross sectional view of one of the forming dogs and its supporting block showing the manner of securing the forming dog therein and the general construction of the supporting block.

Fig. 13 is a fragmental sectional view of the forming mandrel showing the manner of withdrawing the same.

Fig. 14 is a perspective view of a portion of the mandrel showing a sole protector

completely formed located thereon and in 55 the act of being removed therefrom.

Fig. 15 is an enlarged fragmental view of the feeding and roughing roller.

Fig. 16 is an enlarged sectional view of one of the feed roller supports showing the 60 manner of securing the feed rollers and regulating the pressure thereof on the material.

Figs. 17, 18, 19, 20 and 21 are views showing the position of the punching and forming parts during the various stages of operation, and Figs. 22, 23 and 24 are perspective views of the sole protector during its various stages of formation.

In the construction of my device I employ 70 a base 30 to which is securely bolted a column or frame 31. This frame is provided with a pair of parallel upwardly projecting arms 32, which terminate in the bearings 33. These bearings are provided with caps 34 75 and in the bearings 33 is placed the crank shaft 35, the caps 34 holding it in position. The crank shaft consists of the two journals 36, which are supported in the bearings 33, and to which fly wheels 37 are secured. On 80 the inner ends of the journals 36 are formed discs 38, which discs in turn are connected together by the shaft 39, this shaft being offset from the center of the discs. Secured to the shaft 39 is the bearing 40, which terminates in a cylindrical projection 41 and in this projection is secured the connecting rod 42. This connecting rod is provided with screw threads which are screwed into the cylindrical projection 41, and the connecting 85 rod is locked in position against accidental removal therefrom by means of a lock nut 43. The purpose of this construction is to allow a certain amount of adjustment which is necessary in order to bring the working parts of the forming mechanism in proper relation to each other. The lower end of the connecting rod 42 is provided with screw threads and over these screw threads is secured a socket 44. This socket after being 90 placed in position is secured to the connecting rod by means of a pin 45^a which extends through the socket and connecting rod. The lower end of the socket 44 is provided with a ball 45, this ball fitting in a socket 46 formed in the press-head 47. The ball 45 is secured within the socket 46 by means of 95 the plate 48, this holds the ball against re-

100

105

removal from the socket but at the same time allows play therein. This ball and socket connection is made necessary by the fact that the connecting rod 42 must be adjusted 5 after the machine has been assembled. The upper portion of the press head 47 has secured thereto the punch-carrying head 49. This punch-carrying head is provided with a screw threaded portion 50 over which a 10 sleeve 51 is secured. This sleeve is so constructed as to be tightened with a spanner wrench and is for the purpose of securing the punch 52 to the punch-carrying head. The frame 31 is provided with a vertical 15 slot 53 in which the press head 47 and punch-carrying head 49 are located, and in which they reciprocate vertically. The press head and punch head are secured in this slot by means of a plate 54, which is bolted to the 20 frame, this plate forming a closed channel in which the head works. The frame is also provided with cutaway portions or recesses 55, 56 57 and 58, the purpose of which will be explained in detail later. The recesses 55 and 56 extend backward into the frame 31 to a point which will bring them on a level with the press head 47, thus leaving the inverted L-shaped projections 59. Secured on top of the L-shaped projections 59 25 is the die block 60 which is secured thereto by means of screws passing through the openings 61. This die block is provided with a central opening 62 and in the upper face is formed a rectangular recess 63 in 30 which the die 64 is secured, the opening in the die registering with the opening 62. This die block is T-shaped, which prevents it from shifting sideways after being placed in position, and in the lower part of the 35 block is formed a pair of rectangular recesses 65 in which are secured plates 66. The purpose of these plates is to receive the punched wear plate or sole protector, as illustrated in Fig. 18. It will be noted from 40 Fig. 7 that the edges 67 extend over the opening 62 a trifle so as to catch the edges 68 of the sole protector 69. These edges also have an additional function, which will be explained in detail later. Immediately above 45 the die block 60 and secured to the face of the recess 55 is the stripper plate 70. This stripper plate is provided with an opening 71, which registers with the opening formed in the die 64 and with the passageway 72, which allows the material to pass through. 50 The purpose of this stripper plate is to prevent the lifting of the material while the punch is being withdrawn therefrom, and also to act as a guide for the material while 55 it is being fed upward. Within the recesses 56 are secured blocks 73, one edge of which is slotted as at 74. This slotted edge receives the forming dogs 75. The forming dogs are held in position by means of pins 76. 60 These pins are provided with a head 77 which

fit within a counter-bore 78 formed on the inner face of the block 73. This construction prevents the pin 76 from becoming dislodged as the head 77 contacts with the face of the recess 56 when the block has been secured in position. This is accomplished by means of the bolt 77^a, which passes through the opening 78^a formed in the block 73 and is received by the screw threaded opening 79. Secured to the lower end of the press head 47 is a bifurcated member 80. This bifurcated member 80 is spaced from the head 47 by means of the spacer block 81, the spacer block and bifurcated member are, however, secured to the head 47 by means of screws 82.

The upper ends of the bifurcated member or fork 80 are curved, as indicated by the numeral 83. This is for the purpose of bringing the dogs back into the position, as shown in Fig. 17 after the dogs have swung apart as in Fig. 18. The dogs 75 are provided with a perforated ear 84 through which the pin 76 passes. The face of the dogs 75, opposite the ear 84, is provided with a recess 85 and a projecting tip or tongue 86; the purpose of this is to give the object punched its final and finishing touches. The face 87 of the dogs is cut away, as indicated by the numeral 88, leaving a flat face 89, which is somewhat deeper than the face 87; this is to allow the stripper 90 to pass behind the dogs so that the finished article can be removed from the mandrel 91. These dogs are also provided with the extensions 92 which enter into the slot 93 formed in the bifurcated member 80. It is also through this slot that the stripper 90 passes when the fork 80 is raised to its uppermost position. Secured to the press head 47 is a block 94. This block is positioned at a short distance below the projecting end 95 of the mandrel 91 and is for the purpose of preventing the sole protector from falling downward before it has been brought in contact with the dogs 75. The block 94 is of such size that it will readily pass in the space 96 left between the two dogs 75 when they are in closed position. Formed through the head 47 is an opening 98 through which the mandrel 91 passes. As is clearly shown in Fig. 14 the end 95 of the mandrel has its underside flat, while the upper surface is curved. This gives the prongs of the sole protector their curvature, and when the mandrel 91 moves downward with the head 47 the completed protector comes in contact with the stripper 90 and is forced from the mandrel and discharged out of the machine. The mandrel 91 is provided at its rear end with projections 99, which have their lower portions inclined as at 100. This is for the purpose of riding up on the inclined blocks 101, which are secured to the back 102 of the frame 31. Formed integral with the mandrel 91 is a screw 105 110 115 120 125 130

threaded rod 103, which rod passes through a bracket 104. Secured to the press head 47 and between the bracket 144 and mandrel 91 is interposed a coil spring 105. On the screw threaded end of the rod 103 is placed a stop 106, which is held in position by means of the nut 107. This stop is designed to contact with the trip lever 108, which is hingedly attached to the bracket 104 at the point indicated by the numeral 109. Formed integral with the trip lever 108 is a pair of projections 110, which are designed to contact with the tapered block 111 which is secured to the machine frame. Between the projections 110 is secured a perforated plate 112 through which the screw threaded rod 113 passes. This rod is secured to the bracket 104 and has on its outer end the nut 114 and between the nut 114 and plate 112 is placed a coil spring 115, the purpose of which is to tilt the trip lever downward and hold the stop 106 so that the mandrel 91 will be retained in its withdrawn position until the projections on the bracket have contacted with the tapered block 111 when the mandrel is released and assumes its operating position. Secured on the crank shaft 35 is a gear 116, which gear meshes with a second gear 117. The gear 117 being secured to one of the arms 32 of the frame. Attached to the gear 117 is a connecting rod 118, which has its opposite end connected to a ratchet pawl 119. This pawl contacting with the teeth formed on the ratchet wheel 120. This ratchet wheel is mounted on the feed shaft 122, which shaft is mounted in the bearings 123. Approximately the center of this shaft is a knurled enlargement 124, the purpose of which is to grip and feed the material, as well as roughing the surface with which it contacts. Adjacent each side of the knurled portion 124 are formed collars 125, which are designed to contact with blocks 126 mounted in the supporting brackets 127. This will keep the feed roller from shifting sideways. Mounted in the brackets 127 is a second pair of blocks 128, which carry a smooth pressure roller 129, the pressure imparted to the pressure roller being governed by the set screws 130. Connecting the brackets 127 with each other is a bar 131, and through this bar is secured the stem of a lubricator 132. The object of this lubricator being to allow oil, or other lubricant, to drop slowly on the pressure roller and spread a thin film of oil on the upper surface of the material as it is fed into the machine. This supplies sufficient lubricant for the stamping and forming operation that the material has to undergo so that no further oiling of the material is necessary. Secured across the vertical faces of the brackets 127 is a bar 133 to which are secured the guides 134. These guides assist in keeping the material in line. Formed through the back 102 is an opening 135 which is in alignment with the guides 134 and the slot 72 of the stripper plate and to the rear of this opening and registering there what is called a throat 136. This acting as a guide for the material after it has passed through the feed rollers. The press head 47 is provided with an elongated opening 137. This allows the material to pass through the head during the reciprocation of the head. The back 102 is also provided with an elongated slot 138 through which the mandrel 91 and bracket 104 pass, the blocks 101 being located on either side of this slot. In the recess 57, formed in the frame 31, is located a bar 139. The purpose of this bar is to prevent the lower end of the press head from tilting outwardly, it contacting with the fork 80, and to this bar 139 the stripper is secured. The hood 140 is also secured to this bar and serves the purpose of receiving the finished article after it has been removed by the stripper, and directing it downward and outward from the machine. This hood is necessary because of a certain amount of force required to drive the finished article from the mandrel, which causes the article to be forcibly expelled, and were this hood not used the articles would be projected quite a distance across the floor. This hood also makes it possible to place a receptacle in front of the press for receiving the finished articles.

In operating my device the material used comes in long strips or in rolls, and the feeding mechanism is so arranged as to intermittently feed the material forward under the punch so that one man can take care of a number of presses, his only duty being to see that the material is supplied when exhausted and that the containers receiving the finished articles are removed when filled. The recess 57 is for the purpose of allowing the fork 80 to travel up and down with the press head. Through the lower part of the die block is formed the opening 141. This is for the purpose of allowing the end 95 of the mandrel 91 to pass therethrough and above the plates 66 so that the undersurface of the projection 95 will be above the upper face of the sole protector 69.

The operation of my device is as follows: After the machine has been assembled, the connecting rod 42 is adjusted, drawing up or pushing down the press head 47, so that the portion 95 of the mandrel 91 will enter the slot 141 at a short distance above the plates 66. The machine is now ready to be placed in operation. After the machine has been started a strip of metal is fed between the feed rollers 124 and 129. These are driven intermittently by means of the ratchet and pawl mechanism, and the material is fed forward just far enough so as to supply sufficient metal to stamp out the article. When the metal reaches the punch and die the descending of the punch will stamp out

a portion of the metal, as that shown in Fig. 22. This stamped-out portion will fall downward through the opening 61 and leave the projecting ends 68 rest on the plates 66. 5 This downward movement also causes the withdrawal or rearward movement of the mandrel 91. On the upward stroke after the punch 52 has cleared the metal being fed into the machine, the pawl and ratchet 10 mechanism is brought into operation and the material fed forward ready for the next punching operation. As the press head 47 reaches its highest point, the projections 110 come in contact with the block 111, thus 15 tilting the trip lever 108 upward or to a horizontal position, as shown in Fig. 3. This will release the mandrel 91 and will allow it to move forward, as shown in Fig. 3, with the end 95 above the punched article. The 20 machine now commences on the downward stroke, the mandrel 91 is carried downward by the press head 47, the edges 67 of the plates 66 being closer together than the entire length of the punching 69, the ends 68 25 of the punching are bent at right angles to the main body of the punching 69, as shown in Fig. 23; the continued downward movement of the mandrel will then bring the punching into contact with the forming dogs 75 and the recess 85, and the projecting tip 86 of these dogs is so arranged that the lower portion of the mandrel can enter freely, and as soon as the mandrel contacts with the lower edge of the recess 85, the fork 30 80 has traveled sufficiently far to release the ends 92, the mandrel continuing to descend will force these dogs apart so that they will assume the position shown in Figs. 18 and 21. During this forcing apart of the dogs 35 75, the projecting ends 68 will be pressed tightly between the tips 86 of the dogs 75 and the curved portion 95 of the mandrel 91. This will squeeze the metal so that the ends of the projection 68 are brought to a 40 driving or cutting point, as shown in Fig. 24. The stripper 90 extends behind the dogs in the cut away portion 88 thereof, and as the mandrel continues to descend the fork portion of the stripper engages with the inner 45 end of the formed article, and due to the incline of this fork as well as the withdrawal of the mandrel, immediately after the formation of the article has been completed, the article is removed from the mandrel and discharged outwardly to the hood, or shield 140 and then downward into a receiving container. When the mandrel 91 50 has been withdrawn the block 106 carried by the rod 105 is pushed backward so as to release the trip lever 108. The spring 115 now comes into action and tilts the projections 110 inward, as shown in Fig. 13. This will hold the mandrel 91 in withdrawn position until the return upward stroke when 55 the mandrel has passed a point above the

finished object lying on the plates 66. Then the projections 110 contact with the block 111 and throw the trip lever upward, allowing the mandrel to be projected over the work and ready for the next downward stroke. 60

By this operation it will be seen that a complete article is formed by every stroke of the press head, with the exception of the first stroke, which only punches and does not 75 form. But, every succeeding stroke both punches and forms.

My object in curving the arms of the fork 80 80, as at 83, is to assist in bringing the dogs to closing position since the ends 92 of the dogs will ride on this curved surface on the upward stroke and guide them into the fork 93 and thus hold the dogs secure in the position as shown in Fig. 17 until the fork 85 has passed the lowest point of the arms or projections 92, when the dogs will be enabled to swing open, as shown in Figs. 18 and 21. Referring to Figs. 17, 18, 19, 20 and 21:

Fig. 17 shows the commencement of the operation; that is, the material is fed under the punch and the punch is ready to descend. 90

Fig. 18, the punch has descended through the material and the punched article is lying on the plates 66. This shows the dogs in open position. 95

Fig. 19 shows the punch again at its highest position and the end 95 of the mandrel 91 above the punched article. 100

Fig. 20 shows the punch and mandrel partially descended and shows the ends of the punched article at right angles to the main body portion thereof. 105

Fig. 21 shows the finished article in position on the end 95 of the mandrel in the act of leaving its final contact with the dogs 75. 110

An important feature of my device is the speed with which the finished articles can be turned out, and this is limited only by the ability of the punch and dogs to withstand the strain due to their heating and is also limited by the heating of the material used as this will also impart heat to the working ports. 115

Having fully described my invention what I claim is:

1. A combined punching and forming press comprising a base, a frame secured thereto, a press head reciprocally mounted in the frame, a punch head secured to the press head, a punch carried by the punch head, a die secured to the frame and beneath the punch, a pair of forming dogs secured to the frame and located beneath the die, and a mandrel for carrying the article punched past the forming dogs, said dogs adapted to sharpen and give the article its final shape. 120
2. A combined punch and forming press comprising a base, a frame secured thereto, a press head reciprocally mounted in the frame, a crank shaft mounted in the frame, 125

and above the press head, a connecting rod for connecting the press head and crank shaft, a punch head secured to the press head, a punch carried thereby, a die block secured to the frame and beneath the punch, a die secured in the die block, a pair of forming dogs pivotally secured to the frame below the die block, a mandrel projecting through the press head, means carried by the frame for drawing the mandrel backward and into the press head, means for forcing the mandrel forward, said mandrel adapted to carry the article punched past the forming dogs, said forming dogs adapted to 15 sharpen and give the article punched its complete shape.

3. A combined punching and forming press comprising a base, a frame secured thereto, a press head reciprocally mounted in the frame, a crank shaft mounted in said frame and above the press head, a connecting rod for adjustably connecting the press head and crank shaft, a die block secured to the frame and beneath the punch, a die located in the upper portion thereof and in direct alignment with the punch, a pair of supporting plates secured to the lower side of the die block and in alignment with the die, said supporting plates adapted to receive the article punched, a mandrel capable of lateral movement carried by the press head, means carried by the mandrel for projecting it forward over the article resting on the supporting plates, a pair of forming dogs secured to the frame and below the supporting plates, said forming dogs adapted to contact with the punched article while it is being carried downward by the mandrel, whereby the article is shaped and sharpened, means carried by the frame for moving the mandrel in a retrograde movement, means carried by the frame for removing the finished article from the mandrel, and a feeding means for intermittently feeding material beneath the punch.

4. A combined punching and forming press comprising a base, a frame secured thereto, a press head reciprocally mounted in the frame, a punch head secured to the press head, a punch carried by the punch head, a die block secured to the frame beneath the punch, a die mounted in the die block, a pair of forming dogs located be-

neath the die, means for carrying the article punched past the forming dogs, which dogs are adapted to form and sharpen the article, and means carried by the frame for intermittently feeding material beneath the punch.

5. In a combined punch and forming press comprising in combination with a punch and die, a die head and the frame in which the die head is mounted, of a mandrel extending through said die head and movable horizontally therein, and a pair of forming dogs pivotally secured to the frame beneath the die past which the mandrel is adapted to carry the punched article said dogs adapted to sharpen said punched article and give it its final shape.

6. In a combined punch and forming press comprising a frame, a die secured thereto, a punch head reciprocally mounted in the frame, a punch carried thereby, a mandrel mounted in the punch head and slidable horizontally therethrough, means carried by the frame and punch head for imparting the sliding motion to the mandrel, a pair of dogs pivotally secured to the frame and below the die, said dogs adapted to simultaneously give the punched article having driving points formed integral therewith its final shape and sharpen the driving points thereof when brought in contact therewith by the mandrel, and means carried by the frame for removing the finished article from the mandrel.

7. A combined punch and forming press comprising a frame, a die carried thereby, a punch head mounted in said frame, a mandrel extending horizontally through said punch head below the die, said mandrel capable of being moved horizontally through the punch head, a pair of pivotally mounted dogs carried by the frame, between which said mandrel is adapted to pass, said dogs giving the punched article having driving points its finished shape and sharpening its driving points while said article is being carried past the dogs by the mandrel, means carried by the frame and punch head for imparting a horizontal movement to the mandrel.

In testimony whereof, I have signed my name to this specification.

WILLIAM H. BETTS.
